UNITED STATES PATENT OFFICE.

STANLEY J. KEYES, OF NEW YORK, N. Y., ASSIGNOR OF ONE-HALF TO JAMES A. KEYES,
OF NEW YORK, N. Y.

CATHETER DEVICE.

1,032,611.

Specification of Letters Patent. Patented July 16, 1912.

Application filed January 27, 1912. Serial No. 673,846.

To all whom it may concern:

Be it known that I, STANLEY J. KEYES, a citizen of the United States, and resident of the city, county, and State of New York, have made certain new and useful Inventions Relating to Catheter Devices, of which the following is a specification, taken in connection with the accompanying drawing, which forms part of the same.

10 This invention relates especially to catheter devices comprising a suitable support which may be in the form of a belt adapted to coöperate with the body of a person and a coöoperating holder preferably yieldingly 15 and detachably connected to said support and adapted to receive the male organ of the person, said holder comprising suitable means such as a slotted head adapted to receive and detachably hold a catheter in position, there being preferably a separate valve 20 coöperating with said catheter beyond the head.

In the drawings, showing in a somewhat diagrammatic way an illustrative embodiment of this invention, Figure 1 is a perspective view showing the device in position; and Fig. 2 is an enlarged transverse section through the holder.

The illustrative form of the invention 30 shown in the drawings may comprise a support adapted to coöperate with the body of a person and comprising, if desired, a belt 2 provided with suitable fastening devices such as the tapes or strips 3 and buckles 4 35 to secure the support in position on the body 1 of the person, indicated in dotted lines. The support may also comprise a suitable shield 9 which may be integral with the support or attached thereto as by suitable stitching 10. Suitable additional straps such as 8 and 32 may be used to more securely hold the support in position in connection with suitable tapes or strips 5, 6 and buckles such as 7. The support may be formed with a 40 suitable opening of any desired shape such as the opening 12 shown in the apron or shield portion of the support and suitable members such as the stiffened tongues 13 and 14 of doubled or reinforced fabric may 45 be mounted on the support adjacent this opening as by stitching them to the adjacent portions of the support fabric or material.

A suitable holder adapted to receive the penis or male organ of the person may be mounted on the support in any desired way 55 in coöperation with the support opening, preferably so as to be detachably and swivelingly connected with respect to the support. The holder may, for example, comprise a suitable shield or casing 17 of ebonite 60 or other suitable material preferably of a substantially rigid character, and if it is desired to make the holder longitudinally extensible this may be conveniently effected by providing a suitable frame of any desired character adjustably connected with respect to the other member of the holder. As indicated in Fig. 2 the shield 17 may be provided with suitable guides 18, 33 formed with suitable slots such as 39 adapted to 70 accommodate the yoke arms 11 of the frame which may be of nickel-plated metal strip or any suitable material connected in any desired way as by screws such as 22 with the head 23 of the frame which may be conveniently formed of ebonite. A suitable retainer may be mounted on the shield, and for instance, the retainer 19 may be pivoted in the guide 18 by the pin 36 and may have the catch 37 normally forced by the light 75 spring 38 into holding contact with one of the securing holes 21 in the arm. In this way by pressing upon the retainer to release this catch the frame may be longitudinally adjusted with respect to the casing 80 and held in any desired adjusted position to secure the desired length of the holder to suit various conditions, the holder thus acting to prevent contact or irritation of the organ while allowing access to the desired 85 extent to the end thereof. For this reason the smooth shield should be of ample diameter even in cases of engorgement and the frame is preferably given a skeleton construction, the arms being spaced apart sufficiently to prevent undesirable contact with the organ and also minimizing chafing by 90 the clothing. The holder may be conveniently connected to the support by ordinary swiveling friction fasteners or clasps on the 95 shield and tongues, the clasp buttons 15 being, if desired, secured on the tongues so as to coöperate with the fastener heads 16 on the shield which is preferably formed with 100

a relieved or cut-away portion 35 to facilitate the desired swinging motion of the shield about the fasteners in the projecting tongues on the support.

5 The holder is provided with any desired means adapted to receive and detachably hold a catheter such as 20 inserted into the male organ, the end 34 of the catheter provided with any desired inlet openings such as 33 being inserted to the desired extent so as to preferably penetrate the bladder in the position indicated in Fig. 1. In order to securely hold the catheter in adjusted position the holder may be provided with a suitable slot 24 in the head 23 of such size as to accommodate the catheter and a suitable clamp 26 may be used in connection with the head as by connecting it on the hinged piece 40 secured thereto so that the clamp may 10 move in the transverse slot 27 in the head and engage the catheter sufficiently to hold it in position when the spring holding portion 25 of the clamp is snapped over the co-operating part of the head. A valve of any 15 description may be used on the catheter preferably beyond the head, and a valve such as 27 may be used, the plate 30 being adapted to compress and close the catheter 20 when screwed down by the valve handle 30 or screw 31. This may be released at the 25 desired intervals of several hours or so as to effect urination at normal intervals while the catheter is retained in position by the holder and support so as to cause relatively 30 little discomfort or irritation. This device 35 also allows the parts to be washed and cleaned, and, indeed, the person may be readily bathed with the entire device in position and then by removing the catheter 40 from the slot in the head the support and holder may be removed from the person for a few minutes during which the catheter and valve will remain in proper position. A 45 duplicate support may then be put in place and the holder, after the desired cleaning, 50 may be quickly connected to the support by the detachable fasteners so as to allow the catheter to be again inserted and securely held in the slotted head bringing all the parts into the normal position shown in Fig. 1.

Having described this invention in connection with illustrative embodiments, proportions, materials, numbers and arrangements of parts, to the details of which disclosure the invention is not of course to be limited, what is claimed as new and what is desired to be secured by Letters Patent is set forth in the appended claims.

60 I claim—

1. In catheter devices, a support adapted to co-operate with the body of a person and comprising a belt, a depending shield, straps and flexible tongues, there being an opening 65 in said support co-operating with said

tongues, a shield to receive the male organ of the person, disengageable swiveling fasteners on said tongues and said shield to swivelingly and disengageably connect said shield with said support, slotted guides and 70 a co-operating retainer on said shield, a frame comprising a slotted head and yoke arms co-operating with the slots in said guides and disengageably held by said retainer in longitudinally adjusted position 75 with respect to said shield, a catheter to co-operate with the slot in said head, a hinged resilient clamp on said head to detachably hold said catheter in said slot and a valve co-operating with said catheter beyond said 80 head.

2. In catheter devices, a support adapted to co-operate with the body of a person and comprising flexible tongues, there being an opening in said support co-operating with 85 said tongues, a shield to receive the male organ of the person, disengageable swiveling fasteners on said tongues and said shield to swivelingly and disengageably connect said shield with said support, slotted guides and 90 a co-operating retainer on said shield, a frame comprising a head and yoke arms co-operating with the slots in said guides and disengageably held by said retainer in longitudinally adjusted position with respect to said 95 shield, a catheter to co-operate with said head, a clamp on said head to detachably hold said catheter in said slot and a valve co-operating with said catheter beyond said head. 100

3. In catheter devices, a support adapted to co-operate with the body of a person and comprising flexible tongues, there being an opening in said support co-operating with 105 said tongues, a shield to receive the male organ of the person, disengageable swiveling fasteners on said tongues and said shield to swivelingly and disengageably connect said shield with said support, a frame comprising a head and disengageably held in longitudinally adjusted position with respect to said shield, a catheter to co-operate with said head, a clamp on said head to detachably hold said catheter in said slot and a valve 110 co-operating with said catheter beyond said head. 115

4. In catheter devices a support comprising a belt adapted to co-operate with the body of a person and provided with an opening, a holder disengageably and swivelingly connected to said support adjacent said opening and adapted to receive the male organ of the person, said holder comprising a relatively adjustable head, a catheter to co-operate with said head, a clamp to detachably hold said catheter with respect to said head and a valve co-operating with said catheter. 120

5. In catheter devices a support comprising a belt adapted to co-operate with the 130

body of a person and provided with an opening, a holder disengageably connected to said support adjacent said opening and adapted to receive the male organ of the person, said holder comprising a head adjustably mounted with respect to said support, a catheter to coöperate with said head

and a clamp to detachably hold said catheter with respect to said head.
